UNITED STATES PATENT OFFICE

ISAAC N. REED AND FRANCIS T. REED, OF SHREVEPORT, LOUISIANA

PLUG VALVE

Application filed April 29, 1931. Serial No. 533,765.

This invention relates to plug valves of the character requiring rotation of the valve member to open and close the valve and has for the primary object, the provision of means for conveniently rotating the valve member for the above stated purpose and at the same time imparting a sliding movement to said valve member for the purpose of loosening or freeing the valve member 10 from its seat when being opened and to assure firm seating of the valve member when being closed thereby obviating any possibility of leakage to occur.

Another object of this invention is the provision of a single operating means for imparting both rotary and sliding movements to the valve member and which may be easily and quickly operated and capable of adjustment to permit the valve member to 20 be adjusted relative to the seat, whereby wear may be compensated for and assuring perfect operation of the valve over a long period of time.

A further object of this invention is the provision of a plug valve of the above stated character which will be simple, durable and efficient and which may be manufactured and sold at a comparatively low cost.

With these and other objects in view, this invention consists in certain novel features of construction, combination and arrangement of parts to be hereinafter more fully described and claimed.

For a complete understanding of our invention, reference is to be had to the following description and accompanying drawings, in which

Figure 1 is a longitudinal sectional view 40 illustrating a plug valve constructed in accordance with our invention.

Figure 2 is a top plan view illustrating the same.

Figure 3 is a fragmentary sectional view 45 taken on the line 3—3 of Figure 2.

Figure 4 is a fragmentary sectional view taken on the line 4—4 of Figure 2.

Figure 5 is a detail view illustrating the cam shaped groove for imparting the sliding movement to the valve member. 50

Figure 6 is a detail sectional view illustrating the lugs fitting within the groove.

Figure 7 is a side elevation illustrating an adjusting nut.

Referring in detail to the drawings, the numeral 1 indicates the body of the valve having the ports 2 and valve seat 3 of tapered formation to receive a valve member 4 of the plug type having a passage 5 therethrough adapted to be moved into and out of registration with the ports 2. The plug 4 is of tapered formation and carries a stem 6 which extends outwardly of the body by way of the neck 7 and the latter is provided with a marginal attaching flange 8. 65

A bonnet 9 is mounted on the body 1 and includes a tubular extension 10 fitting within the neck 7 of the body 1 and has formed thereon a flange 11 to rest on the flange 8. 70 The flanges 8 and 11 have a gasket therebetween and are secured together by stud bolts 12. The tubular portion 10 has formed integral therewith a stuffing box 13 slidably receiving the stem 6 and has packing 14 located therein. The packing 14 is adjusted 75 and retained within the stuffing box 13 by a gland 15 provided with oppositely extending arms 16 and apertured to receive adjustable fasteners in the form of bolts 17 having nuts 18 threaded thereon and are also pivoted to the bonnet 9 as shown at 19, thus it will be seen that the packing 14 may be placed under a desired pressure to establish a leak-proof connection between the stem 80 and the bonnet and may be replaced by other packing when worn by removing the gland 13. 85

Spaced arms or supporting members 20 are formed integrally with the flange 11 or 90 form a part of the bonnet and carry a housing

21 through which the stem 6 extends and has its opposite faces opened to permit the operation of a segmental gear 22. The segmental gear is splined to the stem 6 and is held 5 against endwise movement by the housing 21 and meshes with a worm 23 of a worm shaft 24. The shaft 24 is journalled in bearings 25 carried by the bonnet or housing 21 thereof and has secured to one end a hand wheel 26. 10 A sleeve 27 is formed integral with the housing 21 and has removably mounted therein pins 28 adapted to fit in a cam shaped groove 29 formed in an adjusting member 30. The adjusting member extends into the 15 sleeve 27 and is secured to the stem 6 so that when the stem 6 is rotated by the hand wheel 26, a sliding movement will be imparted to the valve member due to the cam shaped groove 29 moving relative to the pins 28. An 20 adjusting nut 31 is threaded to the stem and is rotatably secured to the adjusting member 30 whereby the plug 4 of the valve member may be adjusted relative to the seat 3.

25 The segmental gear 22 is adapted to be rotated in either direction by the hand wheel 26 and is limited in its movement by a stop 32 located within the housing 21. The cam groove 29 has its opposite walls shaped to form angularly disposed faces for the pins 28 to engage. The cam faces are so arranged that the valve stem when rotated for opening and closing the valve, the stem will be given a sliding movement. During the rotation of the valve 30 member to open the valve said valve member will receive first a sliding movement away from the seat and then toward the seat as the valve member reaches an open position and corresponding sliding movements to the valve member will be had when the latter is 35 moved from a valve opening position to a valve closing position. This particular operation renders the rotation of the valve member comparatively easy and assures tight engagement between the valve member and its seat when either in a valve opening position or a valve closing position. 40 45 100 105 110

50 While we have shown and described the preferred embodiment of our invention, it will be understood that minor changes in construction, combination and arrangement of parts may be made without departing from the spirit and scope of our invention, as claimed. 115

55 Having thus described our invention, what we claim is:

60 A valve comprising an open body having ports, a tapered seat in the body, a tapered valve member in the body engaging the seat for controlling the ports, a stem on the valve member and extending exteriorly of the body, 65 a bonnet closing the body and receiving the stem, adjustable packing means between the bonnet and the stem, means carried by the bonnet to rotate the valve member in either 70 direction, an adjusting member having a cam 75 80 85 90 95 100 105 110 115 120 125 130

shaped groove slidably mounted in the bonnet and splined to the stem, pins on the bonnet and fitting in the groove to impart a sliding movement to the valve member during the rotation thereof, and means rotatably secured to the adjusting member and threaded to the stem whereby the valve member may be adjusted relative to the seat. 70

In testimony whereof we affix our signatures.

ISAAC N. REED.
FRANCIS T. REED.
